UNITED STATES PATENT OFFICE.

FREDERICK E. KOHLER, OF CANTON, OHIO.

DESIGN FOR A HINGE.

SPECIFICATION forming part of Design No. 28,418, dated March 29, 1898.

Application filed January 28, 1898. Serial No. 668,353. Term of patent 7 years.

To all whom it may concern:

Be it known that I, FREDERICK E. KOHLER, a citizen of the United States, residing at Canton, in the county of Stark and State of Ohio, have invented a new and original Design for Hinges, of which the following is a specification.

My invention relates to a new and original design for a hinge; and it consists of a hinge of the configuration and ornamentation shown in the accompanying drawings, in which—

Figure 1 is a side elevation of a hinge, illustrating my invention. Fig. 2 is a cross-section.

The leading feature of my design consists in base-plates formed with ogee curves on their outer edges and with a stippled ground-work, longitudinal vertical ribs along their adjacent edges having transverse flutes or

scallops, a centrally-disposed longitudinally-fluted double-truncated conical body, the truncated ends of which connect and the flutes of which merge into each other to form uninterrupted longitudinal ribs, and the conical heads at the upper and lower ends of the double-truncated conical body having spherical knobs.

What I claim is—

The design for a hinge, as herein shown and described.

In testimony whereof I have hereunto set my hand in the presence of two subscribing witnesses.

FREDERICK E. KOHLER.
